(57) **CLAIM**

The ornamental design for a faucet attachment, as shown and described.

DESCRIPTION

FIG. 1 is an oblique view of one embodiment of the invention;

FIG. 2 is a left side elevation view of the invention shown in FIG. 1;

FIG. 3 is a front side elevation view of the invention shown in FIG. 1;

FIG. 4 is a back side elevation view of the invention shown in FIG. 1;

FIG. 5 is a right side elevation view of the invention shown in FIG. 1;

FIG. 6 is a bottom view of the invention shown in FIG. 1; and,

FIG. 7 is a top view of the invention shown in FIG. 1.
